UNITED STATES PATENT OFFICE.

HENRY PRICE BALL, OF PITTSFIELD, MASSACHUSETTS, ASSIGNOR TO GENERAL ELECTRIC COMPANY, A CORPORATION OF NEW YORK.

ELECTRICALLY-HEATED OVEN.

1,094,771.

Specification of Letters Patent. Patented Apr. 28, 1914.

Application filed March 17, 1913. Serial No. 754,701.

To all whom it may concern:

Be it known that I, HENRY PRICE BALL, a citizen of the United States, residing at Pittsfield, in the county of Berkshire, State 5 of Massachusetts, have invented certain new and useful Improvements in Electrically-Heated Ovens, of which the following is a specification.

My invention relates to electrically heated 10 cooking devices, and more particularly to electrically heated ovens provided with electric resistance units and are suitable for operations such as broiling, roasting and baking.

15 The object of my invention is to provide an oven in which the same heating unit or units may be efficiently utilized for any of the aforesaid operations.

In performing such operations as broiling 20 it is desirable that a unit be located at the top of the oven so that the heat may be showered down upon the article to be broiled. In operations such as roasting, on the contrary, it is desirable that the unit 25 be vertically disposed so that the distribution of heat be as uniform as possible. In both the broiling and roasting operations it is desirable that the heating unit be located as close as possible to the article being 30 cooked. In certain other operations such as baking which do not require as high heat and which require more space the heating units should preferably be located at a greater distance from the aforesaid articles.

35 According to my invention a pair of substantially flat electric resistance heating units are pivotally mounted in the oven in such a way that they may be swung to horizontal or vertical positions therein. The 40 pivotal mounting is such that when the units are in their vertical position, there is just enough space between them for the pan which is to hold the roast. To provide for the ready regulation of the distance between 45 the article to be cooked and the units in their horizontal positions, I provide a removable shelf and a series of superposed supports therefor.

50 My invention will be more thoroughly understood by referring to the accompanying drawings in which—

Figure 1 is a transverse vertical section and Fig. 2 is a longitudinal vertical section of an oven embodying my invention.

In the drawing 10 and 11 are inner and 55 outer metallic shells between which is packed any suitable heat insulating material 12 to form the stationary casing of the oven. An electric furnace sublimation product containing silicon such as that disclosed in 60 Arthur application, Ser. No. 718,825, filed Sept. 6, 1912, and which has a very high insulation value would be suitable for this purpose. Within the oven are mounted two 65 electric resistance heating units 13, one being mounted on the top wall of the oven and the other on the bottom of the same. These units may be such as that disclosed in Cubitt Patent #964,759. Each of the said units is pivotally mounted at 14 and spring latching means 15 serves to hold each of the units in its horizontal position. The pivotal axes of the units are in opposite sides, that of the top unit being located at the left thereof and that of the other at the right thereof. 70 When the units are in vertical position, a compartment is formed therebetween of substantially the width of the units, or somewhat wider if so desired. As shown in dotted lines in Fig. 1, the upper unit may be 75 swung upwardly and the lower unit downwardly to a vertical position. The conductors 16 which serve to connect the resistance elements of the heating units to the external circuit extend through metal bushings 80 17 and are attached to insulating plugs 18 fitting therein. The said bushings are located in line with the pivotal axes of the respective units. A series of superposed supporting flanges 19 are located on each 85 side of the oven and a removable shelf 20 is adapted to be supported thereby.

When it is desired to perform the broiling operation, the article to be broiled may be placed upon the shelf 20, and the distance 90 from the heating units adjusted by placing the said shelf upon any desired pair of the supports 19. A baking operation may also be performed with the units in a horizontal position. When it is desired to perform an operation such as roasting, the shelf 100 20 should be removed from the oven. The heating units should then be swung to their vertical positions. The roast supported by the usual drip pan may then be placed between the units. It has been found that the roasting operation may be performed in an apparatus such as that above described at 105

2
a very low cost per pound. This is due to the fact that a restricted roasting compartment is formed by the heating units, thus reducing the intervening air space and causing the heat to be very efficiently conducted to the roast.

Various modifications of the above described structure will readily suggest themselves to those skilled in the art, in order 10 to be considered as coming within the scope of my invention set forth in the following claims.

What I claim as new and desire to secure by Letters Patent of the United States is:—

15 1. An electrically heated oven comprising a stationary casing, a substantially flat resistance heating unit mounted therein, means whereby the said unit may be made to assume a substantially horizontal or a substantially vertical position as desired, and means for supporting an article to be heated within the casing when the unit occupies either position.

20 2. An electrically heated oven comprising a stationary casing, a substantially flat electric resistance heating unit pivotally mounted therein, the pivotal axis being substantially horizontal, and means for supporting an article to be heated within the

casing when the unit occupies either position. 30

3. An electrically heated oven comprising a stationary casing, a pair of substantially flat electric resistance heating units pivotally mounted therein adjacent opposite walls thereof, the pivotal axes being located at opposite sides of the respective units. 35

4. An electrically heated oven comprising a stationary casing and a pair of flat electric resistance heating units movably mounted 40 therein so as to assume either horizontal or vertical positions and spaced apart to receive the articles to be heated between them in either position of said units.

5. An electrically heated oven comprising a stationary casing and a pair of flat electric resistance heating units pivotally mounted therein so as to form either horizontal or vertical parallel walls spaced apart 45 to receive the article to be heated between them in either position. 50

In witness whereof, I have hereunto set my hand this 11th day of March, 1913.

HENRY PRICE BALL.
